UNITED STATES PATENT OFFICE.

AXEL JOHNSON, OF OAKLAND, CALIFORNIA.

WASHING MACHINE.

Application filed August 26, 1924. Serial No. 734,198.

To all whom it may concern:

Be it known that I, AXEL JOHNSON, a citizen of the United States, residing at Oakland, in the county of Alameda and State of California, have invented certain new and useful Improvements in Washing Machines, of which the following is a specification.

My invention relates to washing machines of the type adapted for use in the ordinary 10 household wash-tubs.

The object of my invention is to provide a simple, light, and effective machine capable of ready attachment to, and detachment from the ordinary wash-tub. A further 15 object of my invention is to provide for the balancing of the machine in such a manner that its connection with the wash-tub may be of a simple and easily operated form. A still further object is to provide simple means, 20 without unnecessary exposed moving parts, for producing the most effective motion of the dasher. Other objects will become apparent from the following specification.

It is to be understood, however, that the 25 form and construction of the machine herein illustrated and described may be varied, within the limits of the claims hereto appended, without departing from the spirit of the invention as expressed in said claims. 30 With this in view my invention will now be fully described with reference to the accompanying drawings, wherein:—

Fig. 1 is a partly broken vertical section showing my machine attached to a wash-tub.

Fig. 2 is a part sectional plan view of the same.

Fig. 3 is a vertical sectional detail, enlarged, of the dasher oscillating mechanism.

Fig. 4 is a similar view showing the parts 40 in different relative positions.

Fig. 5 is a detail view, enlarged, of the oscillating arm attachment.

Fig. 6 is a horizontal section, enlarged, of the dasher oscillating mechanism.

Fig. 7 is a horizontal section, enlarged, of the wringer operating clutch mechanism.

In the drawings, the reference numeral 1 designates a wash-tub of the ordinary household type. A frame or bracket 2 is provided 50 with a simple clamping member, shown in Fig. 1 as a clamping screw 3, adapted to secure said bracket or frame 2 to the upper edge of one of the walls of the tub 1. Extending from one side of the bracket 2 is a 55 base 4 upon which is mounted a motor 5. The shaft 6 of said motor extends forward-

ly therefrom and carries a worm 7 which drives a worm wheel 8 upon a shaft 9, Fig. 2, journalled in the bracket 2.

The worm wheel 8 is provided with a crank 60 pin 10 which carries a trunnion block 11 slidable in a bifurcated arm 12, Figs. 1 and 2; said arm being secured upon an oscillatory shaft 13. Said shaft has secured to its opposite end a collar 14, Figs. 2 and 5. A 65 forwardly extending curved lever or arm 15 is removably secured to said collar 14 by means of a set screw 16. The outer or forward end of said arm 15 thus has an up and down arcuate reciprocating motion. The 70 worm gearing and the bifurcated arm 12 are enclosed in a housing 17, Figs. 1 and 2, preferably formed as a part of the bracket 2.

A fixed arm or bracket 18 extends forwardly from the housing 17 and carries at 75 its outer end a guide member 19, said guide member being mounted in said fixed arm 18 for oscillation in a vertical plane by means of a pin and socket connection indicated at 20 in Fig. 2. The member 19 provides a 80 guide for a vertically slidable spindle 21, Fig. 1, which carries at its lower end a dasher 22 of any suitable form. The spindle 21 is connected with the reciprocating arm 15 by mechanism which imparts both up 85 and down movement and horizontal oscillation to the dasher 22.

This mechanism comprises a collar 23, Figs. 1, 3, 4 and 6, mounted for horizontal oscillation in a trunnion block 24 and secured 90 to the spindle 21 by means of a set screw 25, Figs. 1 and 6. The trunnion block 24 is mounted for vertical oscillation by means of journal pins 26 in the forked or hollow end 15' of the arm 15. Said trunnion block 95 24 is provided with upwardly and rearwardly projecting lugs 27, which carry a pawl 28, Figs. 3 and 4. Said pawl is adapted to engage a ratchet wheel 29 carried by a grooved cam 30, Fig. 6, said cam being rotatably mounted in the forked end 15' of the arm 15. The collar 23 secured upon the spindle 21 carries a cam roller 31 adapted to ride in the groove of said cam 30. Thus as the arm 15 moves up and down in an arcuate path, and as the spindle 21, which also moves up and down with said arm, is guided by the member 19 at a point below the connection between said arm and said spindle, there is set up a relative oscillation or angular movement between said arm and said spindle, and this relative angular movement 10 11

causes the pawl 28 to rotate the cam 30 in a step by step motion. This rotation of said cam produces a horizontal oscillation of the spindle 21 so that said spindle, and the dasher 22 carried thereby, are caused not only to reciprocate vertically, but also to oscillate horizontally, and this double motion is produced entirely by the single vertical reciprocation of the arm 15. The mechanism above described is adequately enclosed, as shown, by the forked or hollow end 15' of the arm 15.

In order to provide means for operating a wringer of the usual well known type, a clutch mechanism, indicated in Fig. 2, and illustrated in detail in Fig. 7, is provided upon the end of the continuously rotating shaft 9. Said clutch mechanism comprises a jaw member 32 secured upon the end of the shaft 9, and a complementary jaw member 33 secured, as by a set screw 34, upon the wringer shaft 35, upon which is carried one of the usual wringer rolls 36. The wringer shaft 35 is axially movable and is carried by a sleeve 37 surrounding the clutch members 32 and 33 and slidable upon the journal sleeve 38 of the shaft 9. A latch 39 is provided for retaining said sleeve 37 in its innermost position, as shown by dotted lines in Fig. 7, in which position the clutch members 32 and 33 are mutually engaged. It is understood that the wringer may be secured to the wash-tub 1 in the usual manner, and as the details of said wringer do not enter into the present invention, it has been omitted from the drawings, the roll 36 being sufficient to illustrate the connection established by the clutch mechanism above described between the shaft 9 and the wringer.

It is to be observed that the weight of the machine is approximately symmetrical on both sides of the supporting bracket 2 thereof, the motor 5 serving to counterbalance the weight of the dasher 22 and its supporting and operating arms. On account of this balancing of the weight, the bracket 2 can be easily secured to the wall of the tub 1 by the simple clamp shown, thus rendering the attachment and detachment of the machine to and from the tub relatively easy.

For the purpose of heating the water in the tub 1, or for maintaining said water at the desired temperature during the operation of the machine, I may employ an electric immersion heater, of any suitable and well known form, as indicated at 40 in Fig. 1 of the drawings.

Having thus described my invention, what I claim and desire to protect by Letters Patent of the United States is:—

1. A washing machine comprising a supporting member; a substantially vertically reciprocating arm extending therefrom; a dasher pendulously carried by said arm and vertically movable therewith; a fixed bracket disposed parallel with the arm, and affording a guide for the dasher and means actuated by the relative swinging movement between said arm and said dasher for imparting horizontal angular oscillating motion to said dasher.

2. A washing machine comprising a supporting member; a substantially vertically reciprocating arm extending therefrom; a dasher pendulously carried by said arm and vertically movable therewith; and a pawl and ratchet cam mechanism actuated by the relative swinging movement between said arm and said dasher for horizontally oscillating said dasher.

3. A washing machine comprising a supporting member; a substantially vertically reciprocating arm extending therefrom; a dasher pendulously carried by said arm and vertically movable therewith; a rotatable cam carried by said arm; a cam follower carried by said dasher, said cam and said follower co-operating to impart horizontal angular movement to said dasher, and means actuated by the relative swinging movement between said arm and said dasher for rotating said cam.

4. A washing machine comprising a supporting member; a substantially vertically reciprocating arm extending therefrom; a dasher pendulously carried by said arm and vertically movable therewith; a rotatable cam carried by said arm; a cam follower carried by said dasher, said cam and said follower co-operating to impart horizontal angular movement to said dasher, a ratchet associated with said cam; and a pawl actuated by the relative swinging movement between said arm and said dasher for rotating said cam by successive engagements with said ratchet.

5. A washing machine comprising a supporting member; a rotating crank mounted therein; a slotted member adapted to be engaged and oscillated by said crank; a vertically oscillating arm associated with said slotted member; a dasher pendulously carried by said arm and movable vertically therewith; and pawl and ratchet means actuated by the relative swinging movement between said arm and said dasher for imparting horizontal angular oscillating motion to said dasher.

In testimony whereof I have signed my name to this specification.

AXEL JOHNSON.
